UNITED STATES PATENT OFFICE.

THOMAS SIDERITS, OF MILWAUKEE, WISCONSIN.

WALL CONSTRUCTION.

Application filed April 27, 1922. Serial No. 556,943.

To all whom it may concern:

Be it known that I, THOMAS SIDERITS, a citizen of the United States, and resident of Milwaukee, in the county of Milwaukee and 5 State of Wisconsin, have invented new and useful Improvements in Wall Constructions, of which the following is a description, reference being had to the accompanying drawings, which is a part of this specification:

10 This invention relates to improvements in wall constructions and building blocks employed in connection therewith and has for one of its objects to provide a wall which is weather and moisture proof as well as durable.

15 The present type of cement block is constructed in substantially a dry state in order to permit quantity production, as when the mixture is formed with the desired amount 20 of water, the block must remain in the mold for a considerable time before being removed and, therefore, to overcome this blocks are now mixed substantially dry and the mixture pressed into the mold, which forms a very 25 unsatisfactory product.

30 It is one of the objects of this invention to provide a block so designed as to permit the ready withdrawal of the mold therefrom and one in which the desired volume of water 35 may be employed in the mixture to insure production of a block of maximum strength.

Another objection to the present type of 35 block is its weight and this invention has for a further object to provide a block having a plurality of recesses therein whereby the weight per square foot of wall is reduced to a minimum to thus facilitate handling without sacrificing strength.

40 A still further object of this invention is to provide a block of the character described which is reinforced to give added strength and which is capable of use for the face of buildings, especially veneer buildings and which may also be employed for roof tile 45 over a steel frame.

With the above and other objects in view 50 which will appear as the description proceeds, my invention resides in the novel construction, combination and arrangement of parts substantially as hereinafter described and more particularly defined by the appended claims, it being understood that such changes in the precise embodiment of the hereindisclosed invention may be made as 55 come within the scope of the claims.

In the accompanying drawing, I have

illustrated one complete example of the physical embodiment of my invention constructed according to the best mode I have so far devised for the practical application 60 of the principles thereof, and in which:

Figure 1 is a vertical sectional view taken through a wall construction embodying my improved block and constructed in accordance with this invention;

65 Figure 2 is a perspective view of one of the bonding or aligning blocks which I employ, a fragment thereof being broken away and in section to more clearly illustrate details of construction, and

70 Figure 3 is a plan view of one of the building blocks proper, a fragment thereof being broken away and in section to illustrate the manner of reinforcing the same.

75 Referring now more particularly to the accompanying drawings, in Figure 1 of which is illustrated a wall construction embodying my invention, the numeral 5 designates an outer wall and 6 an inner wall formed of opposed complementary blocks 7 held in 80 spaced relation by bonding or connecting blocks 8, the blocks 7 and 8 being of special construction as hereinafter described.

Each block 7 has one face 9 preferably 85 substantially flat and not broken, or formed of any ornamentation should it be wished, and has its other wall interrupted by a plurality of pockets or recesses 10 defined by horizontal and transverse ribs or flanges 11. The side walls of the flanges 11, defining the 90 pockets 10, are tapered to increase the outer area of said pockets for strengthening the ribs and also facilitating the withdrawal of the blocks from their molds as will be readily apparent.

95 As illustrated in Figures 1 and 3, the ribs 11 have reinforcing rods 12 therein which materially add to the strength of the block. As is customary, rods 12 are placed in the mold during the forming of the block.

100 In building a wall in accordance with my invention, first a course of the blocks 7 are laid on a suitable base 13, the blocks of the inner and outer walls having their recessed faces adjacent, and a course of bonding blocks 8 are then laid thereover and secured in place with the usual mortar. The blocks 8 are of peculiar construction whereby the blocks 7 of the inner and outer walls are properly spaced and aligned and the 110 space 17 between the inner and outer walls is made continuous throughout the length

thereof to insure circulation. After the course of blocks 8 has been laid, another course of the blocks 7 is laid and so on until a wall of the desired height has been 5 constructed.

The bonding blocks 8 are also formed with a plurality of transverse and longitudinal ribs 15 which define pockets or recesses 16 in one face thereof, said pockets, 10 however, being in communication with the opposite face of the block by apertures 17 whereby passages through the block are provided. The walls of the apertures 17 and pockets 16 are tapered similar to the walls 15 of pockets 10 in order to properly strengthen the block and facilitate its removal from the mold as is obvious, and the ribs 15 are reinforced by rods 18 placed in the mold before the block is formed.

20 The outer face of the ribs 15 on the side of the block adjacent pockets 16 are centrally provided with longitudinally aligned projections 19 of a width equal to the desired space 14 between the inner and outer 25 walls and in place of the projections 19 on the opposite sides of the blocks 8 I find from experience that the bonding mortar forms an enlargement 20 between the blocks 7 placed thereon which, when set, serves in 30 the place of the projections 19.

What I claim as my invention is:

1. A wall construction, comprising rows of spaced blocks separated by rows of bond-

ing blocks, and a projection on each bonding block of a width substantially equal to the 35 space between the first named blocks and against which the inner faces of the same engage whereby said first named blocks are maintained in proper spaced relation.

2. A wall construction, comprising inner 40 and outer wall members formed of blocks laid in courses, and spacing members interposed between the blocks of adjacent courses constituting said wall members, said spacing members being in the form of skeletonized 45 blocks with vertical air passages therethrough, the upper ends of said air passages being of less area than their lower ends and one face of each of said spacing members having a projection of a width substantially 50 equal to the space between the inner and outer wall members against which the adjacent blocks of the inner and outer wall members abut.

3. A wall construction comprising inner 55 and outer wall members formed of blocks laid in courses, and spacing members interposed between the blocks of adjacent courses constituting said wall members, said spacing members being in the form of skeletonized 60 blocks with vertical air passages therethrough and having spacing projections thereon for the blocks of the adjacent course.

In testimony whereof I affix my signature.

THOMAS SIDERITS.
